UNITED STATES PATENT OFFICE.

PATRICK ALPHONSUS MARTIN AND JOHN STANLEY, OF BIRMINGHAM, ENGLAND.

DESIGN FOR A GOLF-BALL.

44,408.

Specification for Design.

Patented July 29, 1913.

Application filed November 10, 1911. Serial No. 659,660. Term of patent 7 years.

To all whom it may concern:

Be it known that we, PATRICK ALPHONSUS MARTIN and JOHN STANLEY, subjects of the King of Great Britain, residing at Granville street, Birmingham, England, and 137 Ivor road, Sparkhill, Birmingham, England, respectively, have invented a new, original, and ornamental Design for a Golf-Ball, of which the following is a specification, reference being had to the accompanying drawing, in which the figure is an ele-

vation of a golf-ball showing our new design.

We claim—

The ornamental design for a golf ball as shown.

PATRICK ALPHONSUS MARTIN.
JOHN STANLEY.
